A. LLEO ET AL

ENGINE LUBRICATION SYSTEM

Original Filed Jan. 5, 1920

UNITED STATES PATENT OFFICE.

ALBERTO LLEO AND CLAUDIO BARADAT, OF BARCELONA, SPAIN; SAID BARADAT
ASSIGNOR TO SAID LLEO.

ENGINE-LUBRICATION SYSTEM.

Original application filed January 5, 1920, Serial No. 349,652. Patent No. 1,479,918, dated January 8, 1924. Divided and this application filed January 15, 1921. Serial No. 437,484.

To all whom it may concern:

Be it known that we, ALBERTO LLEO and CLAUDIO BARADAT, subjects of the King of Spain, and residents of Barcelona, Spain, have invented certain new and useful Improvements in Engine-Lubrication Systems, of which the following is a specification.

The invention relates to certain improvements in four cycle internal combustion engines of the multi-cylinder, balance-piston type in which the parts are for the most part disposed symmetrically on opposite sides of a transverse medial plane and in which the sets of pistons on each side are connected through a wobble-plate mechanism to translate the reciprocatory movement of the pistons of the adjacent set into rotary movement of a centrally disposed driven shaft.

The present disclosure constitutes a development of the subject-matter contained in our copending applications for internal combustion engines, Serial No. 135,798, filed December 8th, 1916, Patent No. 1,355,484, and Serial No. 219,634, filed February 28th, 1918, Patent No. 1,355,485; and constitutes a division of our copending application Serial No. 349,652, filed January 5th, 1920, Patent No. 1,479,918, on a multi-cylinder internal combustion engine.

A general object of the invention in so far as this divisional application is concerned is to provide in an engine of the type outlined a simple organization of parts in which the movable elements will be efficiently lubricated.

Another object of the invention and still featuring simplicity of parts is to provide for lubricating the movable parts effectively and continuously with the utilization of the least possible power consumption for this purpose and the adaption, as far as possible, of parts structurally necessary in the engine for the additional function of providing parts of the lubricating system.

Broadly, this latter object is attained by making certain of the power transmitting parts of hollow construction and drilling small oil conduits in those other parts which

must necessarily be made of relatively solid 50 construction.

Various other objects and advantages of the invention will be in part obvious from an inspection of the accompanying drawing and in part will be more fully set forth in 55 the following particular description of one form of mechanism embodying our invention, and the invention also consists in certain new and novel features of construction and combination of parts hereinafter set 60 forth and claimed.

Referring to the accompanying drawings:

The figure is a sectional view taken axially of the driven shaft through one physical embodiment of the invention. 65

In the following description and in the claims, parts will be identified by specific names for convenience of expression but they are intended to be as generic in their 70 application to similar parts as the art will permit.

And it will be understood that parts referred to in the specification are in general duplicated at opposite ends of the engine 75 structure.

In the accompanying drawings, there is shown a centrally disposed casting 11, intermediate spacing shells 12 at each longitudinal end of the casting and heads 13 in the 80 form of hollow shells defining the round ends of the casting.

The casting is formed, in effect, of three long, circular walls disposed concentrically about the axis *a*—*b* and including an inner 85 wall 14, an intermediate wall 15, and an outer wall 16. The space between the intermediate wall and the outer wall is divided longitudinally of the axis *a*—*b* to form a plurality of longitudinally extending explosive chambers 17 disposed in a circle about the axis *a*—*b* and each having a relatively small cross-sectional area perpendicular to the axis. The space between the intermediate wall 15 and the inner wall 90 14 is divided by means of a radial partition 18 to form two annular gas conducting passageways 19 and 20. The passageway 19

constitutes a means for conducting fuel to the several explosive chambers. The passageway 20 constitutes a conduit for discharging the burnt gases from the explosive 5 chambers.

Piston cylinders 45 are screwed into longitudinal annular flanges 46, constituting integral parts of the casting and in effect are continuations of the outer and inner walls.

10 A shaft 26 has a central, straight portion 63 rotatably mounted adjacent opposite ends in radial and end thrust bearings 64, carried in the outer end of a centrally disposed shell 65.

15 As is usual with such engines the axially disposed shaft 26 is formed symmetrically with a straight central portion 63, aligned end portions 67 and 68 concentric with reference to the axis $a-b$ and with two inclined portions 69 and 70 extending at the same angle and in opposite directions to each other across the axis $a-b$ and connecting respectively the ends of the straight portion 63 with end portions 67 and 68 as is usual

20

63 with end portions 67 and 68 as is usual
25 in such types of wobbling plate transmission devices. The shaft parts are connected by means of a pair of coating face plates one of which is the face plate 71 formed integrally with and disposed at an angle to
30 the respective inclined portions 69 or 70 of the shaft. The other face plate 72 constitutes a flange from one end of a sleeve 73 which is slid on the adjacent end of the straight portion 63 of the shaft and is held thereto. The parts forming the shaft are made hollow to accommodate the lubricating feature of the invention and are made massive with relatively thick walls so as to
35

40 transmit the heavy strains imposed thereon and at the same time maintain their true symmetrical position with reference to the axis $a-b$ under prolonged and severe working conditions. The central portion 63 is provided at opposite ends with closing plugs

45 78 and thus forms a closed lubricating reservoir 79 within the length of this straight portion in the embodiment of the invention disclosed in the figure.

The inclined portions or crank pins of the shaft are likewise formed of a hollow tubular structure and are closed at opposite ends by means of plugs 80 and 81, thus providing oil reservoirs 82 in each of the inclined crank pin portions of the shaft. Communication is provided between the lubricating reservoir 79 and the reservoirs 82 at opposite ends thereof by means of drillings, one of which 86 extends angularly from the reservoir 79, through the side of the shaft 63, through the sleeve 73, and face plate 71. A lubricant conducting tube 87 is positioned axially in the respective shaft portion 69 or 70, and has its opposite ends inserted in the closing plugs 80 and 81 at opposite ends thereof and by means of a drilling 88 in the

plug 81 one end of the tube is connected with the drilling 86. The outer end of each tube is connected with a supply intake passageway 89 drilled in the otherwise solid shaft end and in the plug 80. This passageway 89 is designed to receive lubricant from a source of supply such as the oil pump 91. 70

The tube 87 is provided with outlet vents 93 to permit the passage of the lubricant into the hollow portion of the crank pin. 75 The crank pin is provided with outlet ports 94 for supplying the bearings 95 and 96 of the wobble plate construction.

The central portion 63 of the shaft is provided adjacent opposite ends with inset plugs 99 which constitute supports for opposite ends of an oil conducting tube 100 axially disposed in the central portion of the shaft and extending substantially for its entire length. This tube is of advantage in tending to reduce the amount of lubricant necessary when shafts having large tubular capacity are utilized.

The shank portions at opposite ends of the inclined crank pins are enlarged to extend outwardly beyond the outlines of the periphery of the pin to form abutments 101 at opposite ends thereof. A hollow, relatively light wobble plate construction of readily demountable and interfitting parts is fitted between the abutments 101 so as to be held against end play. This construction includes two frusto-conical shells 102 and 103 with their small ends projecting outwardly from each other and formed into relatively long hubs 104 engaging the abutments and with their hollow sides facing each other and spaced apart. The bearings 95 and 96 are formed between the hubs and the portions of the pin encircled thereby.

the portions of the pin encircled thereby. By this construction it is possible to mount the wobble plate shells only at the ends of the crank pin, leaving the intermediate part free of frictional resistance and permitting the mounting of an end thrust bearing 105 in the lubricant containing space 106. The lubricant containing space enclosed by the shells is encircled by a relatively thick thrust ring 107 which includes a tubular wall 108, encircling the central portion of the crank pin and fitted at opposite ends in peripheral sockets 109 formed at the periphery of the shells 102 and 103. The space enclosed by the shells 102, 103 and the wall 108 forms the lubricant containing reservoir 106 which is fed from the ports 94 leading from the interior of the pin and the piston rod bearings. It will be noted that the end thrust bearing 105 is positioned within the lubricant containing reservoir and this construction is of material importance when it is considered that the thrust of the pistons on the shaft is usually transmitted through the wobble plate with a decided tendency to distort the plate and thus destroy the effective-

ness of the pre-designed organization. The ring 107 exteriorly of the wall 108 is formed of outwardly extending shell walls 118, which are inclined towards each other and at the jointure of the walls is provided with a circle of spherical sockets 119 one for receiving each of the spherical heads 120 of the longitudinally disposed piston rods 121. Lubricant conducting tubes 122 extend from the wall 108 through the hollow space between the shell walls 118 and open into the sockets 119 to supply lubricant from the reservoir 106 to the several piston end sockets. The pistons 124 are of the conventional trunk type, are reciprocatorily mounted in the piston cylinders 45 and are demountably connected by means of the spherical sockets 125 with the inner ends of the piston rods 121 as is usual in such constructions. It will be appreciated that the lubricant leaking from the exposed front end of the sockets 119 will be splashed by the rocking wabble plate into the open ends of the piston cylinders to lubricate the same as well as the sockets at the piston ends of the piston rods. The wabble plate will also act to splash this leaking lubricant into the adjacent shaft bearings.

There is provided an attachment which includes the lubricant supplying pump 91 which discharges through the tubes 144 into the drilled conduits in the ends of the shaft. The pump is supplied from the bottom of the end shells through a return pipe 145.

In providing for the lubricating system every effort has been made to reduce the amount of lubricant carried and parts which were found necessary in addition to the power transmission parts have been made as light as possible. In general the invention features a refinement in structural organization of an engine of the type disclosed rather than in any improvement in functional operation.

While we have shown and described, and have pointed out in the annexed claims, certain novel features of our invention, it will be understood that various substitutions and changes in the form and details of the device illustrated and in its operation may be made by those skilled in the art without departing from the spirit of the invention.

Having thus described my invention, I claim:—

1. In an internal combustion engine of the wabble plate type, a driven shaft including a central straight portion, angularly disposed portions at opposite ends thereof and straight end portions aligned with the central portion, said central and inclined portions being hollow separate means for closing the ends of the same to form oil compartments therein, intercommunicating means providing for fluid communication between the compartments so that the lubri-

cant will flow from one into another and means for feeding the lubricant through one of the end portions to supply the oil compartment in the adjacent inclined portion of the shaft, wabble plate mountings on said inclined portions of the shaft, said portions provided with vents for supplying the mountings thereon with lubricant from the interior thereof.

2. In an internal combustion engine, of the wabble plate type, a driven shaft including a tubular center portion, plugs closing opposite ends of the same to form an oil compartment, an inclined tubular shaft portion rigidly secured to an end of the center portion, plugs for closing opposite ends of said inclined portion to form another oil compartment and means for placing one of the compartments in fluid communication with the other compartment.

3. In an internal combustion engine of the wabble plate type, a driven shaft including tubular center portion, plugs closing opposite ends of the same to form an oil compartment, an inclined tubular shaft portion, a shank connecting one end of the center portion with the adjacent end of the inclined portion, a plug closing the end of the inclined portion adjacent the shank, said shank and plug provided with oil passageways coacting to provide fluid communication between the oil compartment in the center portion and the inclined tubular shaft portion.

4. In an internal combustion engine of the wabble plate type, a driven shaft including a tubular center portion, plugs closing opposite ends of the same to form an oil compartment, an inclined tubular shaft portion, a shank connecting one end of the center portion with the adjacent end of the inclined portion, a plug closing the end of the inclined portion adjacent the shank, said shank and plug provided with oil passageways coacting to provide fluid communication between the oil compartment in the center portion and the inclined tubular shaft portion, and a distributing tube leading from said last named plug into the interior of the inclined shaft portion and adapted to supply a lubricant to said interior.

5. In an internal combustion engine of the wabble plate type, a driven shaft including a central straight portion, angularly disposed portions at opposite ends thereof and straight end portions aligned with the central portion, said shaft provided within its outlines with a lubricant-conducting passageway for receiving the lubricant in one of the end portions and for conducting the same through the adjacent inclined shaft portion through the central portion and into the other inclined shaft portion and said shaft provided with openings providing direct access to all parts of the passageway and means for closing said openings.

6. In an internal combustion engine of the wabble plate type, the combination of an axially disposed shaft portion and inclined crank pin shaft portions secured at opposite ends to the axially disposed shaft portion, said angularly inclined portions being tubular and opened at opposite ends and removable plugs for closing said ends, one of said plugs provided with an oil conduit 10 for admitting oil to the interior of the respective inclined shaft portion.

7. In an internal combustion engine of the class described, the combination of an axially disposed shaft opened at opposite ends, 15 readily removable means for closing said ends, an oil passageway leading from the interior of said shaft adjacent each of the opposite ends thereof, a pair of tube-supporting-plugs positioned within said shaft 20 and spaced inwardly from the oil passageways at opposite ends, and an oil conducting tube supported at opposite ends by said pair of plugs whereby a lubricant may be introduced through one of said passageways at one end of the shaft and caused 25 to flow into the bore of the shaft, through said tube into the bore at the opposite end and to be discharged through the passageway at said opposite end.

8. In an internal combustion engine of the class described, the combination of an axially disposed shaft portion opened at opposite ends, readily removable means for closing said ends, an oil passageway leading 35 from the interior of said shaft adjacent each of the opposite ends thereof, a pair of tube-supporting-plugs positioned within said shaft portion and spaced inwardly from the oil passageways at opposite ends, and an oil 40 conducting tube supported at opposite ends by said pair of plugs whereby a lubricant may be introduced through one of said passageways at one end of the shaft portion and caused to flow into the bore thereof, through said tube into the bore at the opposite end and to be discharged through the passageway at said opposite end, an inclined shaft portion fixed to one end of the first 45 named portion and opened at opposite ends, means for closing said opposite ends, the means adjacent the first named shaft portion provided with a lubricating passageway designed to be opened to the passageway leading from the first named shaft at the adjacent end whereby the lubricant is passed 50 from the first named shaft portion into the angularly disposed shaft portion.

9. In an internal combustion engine of the wabble plate type, the combination of a shafting including a centrally disposed shaft portion and angularly disposed crank pin portions at opposite ends of the central shaft portion, a wabble plate construction mounted upon each of said inclined crank 55 portions, a plurality of explosive chambers

encircling the centrally disposed shaft portion, balanced pistons facing the opposite ends of said chambers and with a piston of each cylinder facing one of said wabble plate constructions and the other piston of said cylinder facing the other wabble plate construction, a single lubricant supplying means for supplying a lubricant through both of the wabble plate constructions to the several pistons and their containing cylinders and a single pressure means acting on the lubricating supplying means within the shafting for forcing the lubricant through both the wabble plate constructions. 70 75

10. In an internal combustion engine of the wabble plate type, the combination of a centrally disposed shaft portion, a plurality of piston cylinders encircling said shaft portion, extending parallel thereto and all opening in one direction at one end, an angularly disposed shaft portion fixed to the first named shaft portion and facing the exposed ends of the cylinders, a wabble plate construction carried by said angularly disposed shaft portion, a piston in each cylinder operatively connected to the wabble plate construction for translating the reciprocatory movement of the pistons into rotary movement of the shaft, means for supplying lubricant to said wabble plate construction, said construction acting on the lubricant supplied thereto for splashing the same into the exposed ends of said cylinders, a head shell defining one end of the engine and enclosing said wabble plate construction, said shell having internal dimensions closely adhering to the space outlined by the wabble plate construction in its cycle of movement and means at the bottom of the head shell for receiving the drip from the piston cylinders. 80 85 90 95 100 105

11. In an internal combustion engine of the wabble plate type, the combination of a centrally disposed shaft portion, a plurality of piston cylinders encircling said shaft portion, extending parallel thereto and all opening in one direction at one end, an angularly disposed shaft portion fixed to the first named shaft portion and facing the exposed ends of the cylinders, a wabble plate construction carried by said angularly disposed shaft portion, a piston in each cylinder operatively connected to the wabble plate construction for translating the reciprocatory movement of the pistons into rotary movement of the shaft, means for supplying lubricant to said wabble plate construction, said construction acting on the lubricant supplied thereto for splashing the same into the exposed cylinders, a head shell defining one end of the engine and having an internal dimension closely adhering to the space covered by the wabble plate construction said end shell in its cycle of movement and constituting a means for re- 110 115 120 125 130

ceiving the lubrication dripped from the cylinders and to form a pool of lubricant in the bottom of said head shell, said wabble plate construction acting to splash lubricant from the said pool onto the adjacent parts.

12. In an internal combustion engine of the wabble plate type, the combination of a centrally disposed shaft portion, a plurality of piston cylinders encircling said shaft portion, extending parallel thereto and all opening in one direction at one end, an angularly disposed shaft portion fixed to the first named shaft portion and facing the exposed ends of the cylinders, a wabble plate construction carried by said angularly disposed shaft portion, a piston in each cylinder operatively connected to the wabble plate construction for translating the reciprocatory movement of the pistons into rotary movement of the shaft, means for enclosing said cylinders, and wabble plate constructions, said means including an end shell facing the exposed ends of the cylinders and containing said wabble plate construction, means for supplying lubricant to said wabble plate construction, said construction acting on the lubricant supplied thereto for splashing the same into the exposed cylinders, and a pipe connection leading from the bottom of said shell to withdraw lubricant from said pool.

13. In a device of the class described, the combination of a hollow crank pin inclined to its axis of rotation, a hollow wabble plate

construction loosely mounted on said pin and having walls providing a space for containing lubricant, said pin provided with ports for supplying the interior of the wabble plate construction with lubricant 40 from the interior of the pin, an end thrust bearing between the central portion of the pin and a portion of said walls, said bearing disposed within the lubricant containing space within the wabble plate construction. 45

14. In a device of the class described, the combination of a hollow crank pin inclined to its axis of rotation, a hollow wabble plate construction loosely mounted on said pin and having walls providing a space for containing lubricant, said pin provided with ports for supplying the interior of the wabble plate construction with lubricant 50 from the interior of the pin, an end thrust bearing between the central portion of the pin and a portion of said walls, said bearing disposed within the lubricant containing space within the wabble plate construction, said construction being relatively 55 thick along the length of the pin and formed hollow to feature a light construction, said construction provided with exposed bearings for piston rods and provided with lubricant conduits extending across the hollow interior thereof for supplying 60 said bearings from the interior of the pin. 65

This specification signed this 7th day of October, 1920.

ALBERTO LLEO.
CLAUDIO BARADAT.
